UNITED STATES PATENT OFFICE.

JOHN J. HEYS, OF LYNN, ASSIGNOR TO JAMES W. BROOKS, OF PETERSHAM, TRUSTEE FOR THE MCKAY & BIGELOW HEELING MACHINE ASSOCIATION, OF BOSTON, MASSACHUSETTS.

HEEL-PRESSING MACHINE.

SPECIFICATION forming part of Letters Patent No. 530,046, dated November 27, 1894.

Application filed December 1, 1893. Serial No. 492,475. (No model.)

To all whom it may concern:

Be it known that I, JOHN J. HEYS, of Lynn, county of Essex, State of Massachusetts, have invented an Improvement in Heel-Pressing Machines, of which the following description, in connection with the accompanying drawings, is a specification, like letters and figures on the drawings representing like parts.

This invention has for its object to improve the class of machine represented in United States Patent No. 497,497, granted to me May 16, 1893, my improvements simplifying and increasing the durability and capacity of the machine for work. In this my present invention I have provided the heel carrier with suitable means to clamp the heel in a yielding manner after the latter has been fed to the carrier, said heel being clamped while it is being fed into the compressing die, the heel being in practice compressed on all sides.

In my improved machine the stroke of the parts in compressing the heel vertically is substantially the same, and to provide for heels of varying thickness I have arranged to employ a series of tread plates one or more of which may be added to the carrier according to the thickness of the heel; and I have also combined with the hopper to contain the heel blanks adjusting means whereby said hopper, and with it the heel blank feeding device, may be adjusted vertically according to the effective thickness of the tread plate. I have provided means for securely locking the heel seat die in working position, such locking enabling it to effectually resist any lateral displacement during the time that the heel blank is being compressed.

Other features of my invention will be hereinafter described and designated in the claims.

Figure 1 is a view partially in side elevation but chiefly in vertical section, of a machine embodying my invention. Fig. 2 is a detail showing the adjustable hopper; Fig. 3, a section below the dotted line x , Fig. 2. Fig. 4 is a partial front elevation of the machine shown in section in Fig. 1. Fig. 5 is a detail of the devices for moving the feeder. Fig. 6 is a detail showing the dies in plan view, the carrier and the hopper adjusting

mechanism being in section in about the line x' , Fig. 4. Figs. 7, 8, 9 and 10 show respectively a side elevation, plan, and longitudinal section and end view of the blank feeding mechanism. Fig. 11 is a detail illustration 55 of the heel seat die and its actuating devices. Fig. 11^a, is a detail of the rocker lever H ; Fig. 12, details of the heel seat die. Fig. 13 is an under side view of the stationary cross head or abutment. Fig. 14 is a plan view looking 60 upon the dies closed with the heel seat die locked in position; Fig. 15, an enlarged detail of the heel seat die. Fig. 16, is a detail showing the adjustable connection between the links k and the frame-work. 65

The side pieces A of the frame are connected at their upper ends by a stationary cross head A' , and at their lower ends by a fixed cross head A^2 , the said cross heads being firmly connected together by rods A^3, A^3 , 70 held in sockets in the side frames, said rods serving also as guide rods for the movable cross head B to be described. The machine has a suitable shaft B' driven in any usual manner, said shaft having as shown a pinion B^2 which engages a toothed gear B^3 fast on a crank shaft B^4 connected by link B^5 to the pin B^6 forming the junction between the two links B^7, B^8 , constituting what is called a toggle joint, said links being jointed respectively 75 to the movable cross head B and the lower fixed cross head A^2 , as shown, through the intervention of shoes or brackets b, b' . The devices thus far described by letter with the exception of the shoes or brackets, are common to my patent referred to. 85

I have connected the frame sides by means of a girt C to which I have secured a bracket C' , said bracket having a cam slot 2, shown as having substantially straight portions at 90 bottom and top connected by an inclined portion, see Fig. 1, and said bracket has connected to it as shown by stud bolts 3, a cam plate C^2 , shown best in Fig. 11.

The under side of the cross head A' , see 95 Figs. 1 and 13, is in this instance shown as recessed at a to receive the top of the heel seat die D , and said recess is made deeper at its center as at a' to receive the head of the bolt a^2 , used to confine in position on the heel seat 100

die its detachable face *d*, see Fig. 15, said faces being readily changed for heels of different sizes, said faces having preferably at their backs projections as *4*, to enter a recess *5* in the main body of the heel seat die, said projections accurately positioning the faces.

The movable cross head has mounted upon it carriers *i*, *i*, which carry edge compressing dies *j*, *j*, see Fig. 6, said carriers being connected by links *k* with the frame-work, substantially as in my said patent, but herein I have provided for holding said dies in working position in a novel manner, viz:—by bolts *5*, *5*, pinned or jointed preferably by thumb pins *6* at one end to the said dies and extended through the said carriers, said bolts having nuts *7* applied to their ends, said thumb pins being readily removable whenever it is desired to change the dies *j*, *j*.

In practice the die carriers are moved toward and from each other as the cross head *B* is raised or lowered as provided for in my said patent. In this instance of my invention the die carriers *i*, *i*, have at their front ends, see Fig. 6, heavy lugs or projections *8*, to the inner sides of which are applied suitable hardened gibs *10*, which, as the carriers *i*, *i*, are made to approach each other, act upon and grasp the outer side of the breast guide *d*' connected to one end of the body of the heel seat die, said breast guide being preferably integral with said heel seat die, as thereby better work may be done than when the said heel seat die and breast gage are made as separate pieces.

The shape of the breast gage is best shown in Figs. 12 and 14, and it will be seen that said gage has an angular edge *12*, which as the movable cross head *B* rises, passes close to the breast edges of the tread plate *14*, said edge *12* entering a groove or depression *15*, see Fig. 12, below the top of said tread plate. The edge referred to is useful because it acts to cut off or remove any adhering fibers of the leather which may have remained on the tread plate.

In practice, the compressing movement of the parts in compressing a heel vertically, will be the same, but heel blanks will from time to time vary in thickness, and to provide for this I increase or decrease the thickness of the tread plate, the latter being readily detachable from the heel blank carrier to be described. In practice I find it very convenient to make up the tread plate of a series of these plates, two or more, I having shown two plates in the drawings.

The heels to be compressed will be put into a hopper *E*, substantially the same as in my said patent, the sides of said hopper being adjustable by screw *16* on an arm *17* provided, see Fig. 2, with a scale, which, co-operating with the lower end of the side of the hopper, indicates the proper position of the hopper for heel blanks of different height.

The foot of the arm *17* is in this instance secured by bolt *18* to an adjustable table *E'*,

on which slides the heel feeding mechanism to be described, said table having a depending shank *19*, see Fig. 4, which shank is fitted to slide vertically between guides *20*, a screw *21* resting on a suitable seat *22* and engaging said shank being employed to adjust said table vertically and with it the hopper, to thus correctly position the heel blank feeding mechanism according to the thickness of the tread plate and the thickness of the heel blank, said screw constituting one form of adjusting device, but for the screw, I may use any suitable equivalent device. The heel feeder, in this instance of my invention, consists essentially of a plate *e* constituting a heel blank support, see Figs. 7 to 10, said plate,—it lying when at rest substantially under the lower open end of the hopper *E*,—being slotted at *24* for the passage through it of a stud *25* secured in a pusher *e'*, said pusher acting against the edge of the lowermost heel blank in the hopper, and moving it laterally into position on the tread plate *90* referred to, it lying on a projection of what I denominate the heel blank carrier *G*. The stud *25* is surrounded between the pusher and support, see Fig. 9, with a friction washer *26*, preferably of leather or rawhide, and below this support said stud is surrounded by a second washer *27* which may be of wood, said washer being acted upon by a spring *28*, controlled as to its pressure by suitable nuts *29*, said washers constituting a friction device which will cause the supporting plate to be moved until obstructed, in unison with the pusher, as the latter is actuated by the link *30*, jointed to the compound lever *31*, *32*, see Figs. 4 and 5, said lever constituting part of the actuating mechanism for the feeding mechanism. The arm *32* is fixed to a rock shaft *33*, mounted in suitable bearings *83* on the frame, said rock shaft having an arm *34* provided with a roller or other stud which enters a cam groove, not shown, in a suitable cam disk *36*, substantially such a disk as in my said patent.

The arm *31* is jointed by pin *37* to the arm *32* and said arm *31* is made adjustable as to its effective throw by an adjusting device *38* shown as an adjustable screw, one end of which acts against arm *31* when the pusher is being moved forward to feed a heel blank, the screw *38* in ear *39* of arm *32* acting on the arm *31* when the pusher is being retracted. The screw *38* acts to always return the pusher to a common starting point, but by adjusting said screws so as to provide for more or less lost motion between them and the arm *31*, I may move the pusher more or less in the feeding operation according to the size of the heel blank. The stop *40*, see Fig. 9, arrests the support *e* in a definite position as the pusher is retracted. In operation, the supporting plate *e* is moved forward until its end meets the tread plate then opposite it, and thereafter the pusher by its continued movement pushes the blank from said sup-

port onto the tread plate, and under the heel seat die to be described.

To insure the positive retraction of the support *e* the latter has been provided with 5 ratchet teeth as at 41, see Figs. 7 and 8, which are engaged by a pawl 42 pivoted on the pusher and having a pin 43 which rides on a cam plate 44, the latter effecting the disengagement of the pawl from the ratchet teeth

10 as soon as the said support has been retracted sufficiently to not interfere with the movement of the heel carrier, and thereafter the further movement of the support in the same direction is effected by the friction device before described. The carrier *G* is herein represented as a bent lever pivoted at *G'* on a suitable bracket *G²* secured to the movable cross head *B*, as best shown in Fig. 4. The lower end of lever *G* has a roller or other stud *G³* 15 which enters cam groove 2. The pin *G'* also serves as the fulcrum of a rocker lever *H* having a depending arm *h'x* which co-operates with the portion 56 of the cam plate *C²*, said rocker lever having also an arm *h'* which is 20 jointed at 45 to a block 46 into which is adjustably screwed one end of a rod *h²*, the head of which enters a spring case *h³* containing preferably a spiral spring *h⁴*, see Fig. 1, said case having that end through which the link 25 passes made detachable, the rod acting against one end of said spring, said spring and rod constituting a yielding or spring link.

The upper end of the spring link is jointed to a lever *h⁵* pivoted on a link *h⁶* mounted on 30 the carrier *G*, the inner end of lever *h⁵* being jointed at 48 to the combined heel seat die and breast gage.

The rocker lever *H*, see Fig. 11^a, has near the upper end of arm *h'x* and at the inner side 40 of said arm a shoulder 50.

Viewing Fig. 1, showing the movable cross-head in its lowest position; it will be seen that the lower end of arm *h'x* is under the portion 45 56 of the cam plate *C²*, and it will be assumed that a heel blank has been pushed between the tread plate and the heel seat die, and is lightly held there by the stress of spring *h⁴*, but the breast of the heel blank may not be against the breast gage. In this condition 50 the cross head *B* will be moved vertically and the arm *h'x* in the first part of such movement will strike the portion 56 of the cam plate *C²*, and the rocker lever *H* will be turned, and when the lower end of the arm *h'x* rests 55 against the said portion 56 the point 45 of the yielding link will have been moved to the left and downward, see Fig. 1, whereby the rod *h²* is retracted until its head by contact with the case pulls the latter down to release the heel blank and let it move by gravity until the breast of the blank rests against the breast gage. This done, in the further upward movement of the carrier, the roll *G³* will enter the inclined part of groove 2, and the carrier will 60

65 be moved on the pivotal point *G'* in such direction as to carry the heel blank into position between the edge dies, and in such move-

ment the relative positions of the centers of the lower end of the yielding link and the carrier will result in compressing the spring 70 *h⁴*, thus clamping or pinching the heel blank between the heel seat die and tread plate, said clamping action continuing until after the heel has been put into position and compressed, and the carrier has thereafter begun 75 its outward movement.

As the carrier with the compressed heel is being moved outwardly to retract it from the die,—the lower end of arm *h'x* then resting against the portion 56 of the plate *C²*,—the 80 heel seat die will begin to rise, for the strain on the spring link is then exerted downwardly, the said heel seat die rising until the convexed face of the plate *d* is raised sufficiently to free the compressed blank. Substantially as the heel blank carrier reaches 85 its normal outward position, the heel blank feeder commences to move forward to take the heel blank from the hopper *E* and push it toward and to meet the compressed blank 90 then on the blank carrier, and while the pressure on the compressed blank is relaxed, the pusher pushes the edge of the uncompressed blank against the compressed blank 95 and starts the latter from the carrier. The heel seat die is kept elevated until a small portion of the uncompressed heel blank is lodged between the tread blank and the heel seat die, and this effected, the heel seat die will be caused to descend, act on and clamp 100 the uncompressed heel blank, and it will hold said heel blank compressed by a strain measured by the spring *h⁴*, while the pusher in its continued forward movement pushes the heel into place between the tread plate and 105 the heel seat die. It is important to hold the uncompressed blank frictionally, as stated, for otherwise in the quick movement of the machine the said heel blank could not be properly positioned upon the heel blank carrier. 110

In lowering the carrier, as soon as the shoulder 50 on the depending lever *h'x* meets a shoulder 52, see Fig. 11, on the cam plate *C²*, said rocker lever is given a quick turn for a slight distance in a direction to increase the tension of spring *h⁴*, and at the same time put the lower end of arm *h'x* under the portion 56 referred to. The uncompressed heel blank is coming into place between the tread plate 120 and the heel seat die acts against the compressed blank then on the tread and knocks the same off.

The cross head *A'* has attached to its front side by suitable set-screws 100 a guide 101 125 behind which the heel seat die rises while the heel blank is being compressed, said guide preventing any outward slipping of said die, said guide being shown as notched to embrace and steady the lever *h⁵*.

I have before described that the lever 31 130 32 is or will be adjusted one part on the other to enable the pusher to operate properly with a heel-blank of a certain size, in

order that the pusher may correctly place the heel blank upon the carrier, and to properly effect this adjustment accurately, the operator, prior to adjusting the lever 31, 32, will 5 rotate the shaft B⁴ until the point n⁴, shown as marked on the gear B⁸, registers substantially with the finger n⁵, and with the shaft in such position, the pusher being way forward, the operator will make the final adjustment to adapt the pusher for the size of the heel blank thereafter to be used.

The act of compressing the heel blank edge-wise requires the exertion of, it will be understood, very considerable power, and consequently to resist the strain the mechanism employed must be very strong and rigid, and I have aimed to provide means whereby the carriers upon which the edge-compressing jaws are mounted may resist excessive strain, 15 and to do this in the best and most economical manner, I have provided the upper end A²⁰ of the frame-work of the machine, see Fig. 4, with an ear which receives a fulcrum pin 66, which pin pivots the link k of the carrier 25 to the frame-work. In practice I prefer to make this pin with eccentric ends 66, as best shown in Fig. 16, said ends receiving upon them the links k, there being two such links as herein represented in connection with each 30 carrier i. The body of said pin will preferably be of greater diameter than its eccentric ends and will have a driving fit in said ear. By fixing said pin so that it cannot rotate while the machine is in use I am enabled to 35 throw all the wear on the pin and links, and to compensate for this wear and also to enable the faces of the edge-compressing jaws to be accurately adjusted to properly co-operate with the heel blank carrier, I may require,

Having described my invention, what I 45 claim as new, and desire to secure by Letters Patent, is—

1. In a machine for compressing heels, a die to compress a heel edge-wise, and a tread plate, combined with a breast gage having a 50 cutting edge to co-operate with the breast end of the tread plate, substantially as described.

2. In a machine for compressing heels, a die to compress a heel edge-wise, a carrier 55 having a tread plate to receive a heel blank to be compressed and put into the space between the edge compressing dies, and a heel seat die connected to and movable with said carrier, substantially as described.

60 3. The carrier having a tread plate to receive the heel blank to be compressed edge-wise, and a heel seat die to co-operate with said carrier and hold the heel blank while being put into compressing position, combined with devices to support said heel seat die in a yielding manner to thus enable the heel blank to be held frictionally while the

carrier is being moved with the heel blank, substantially as described.

4. The heel blank carrier having a tread 70 plate, the heel seat die, a lever to which it is connected, and a yielding link, combined with a cam, and devices between said cam and link to control the effective force of the said yielding link, substantially as described. 75

5. The heel blank carrier having a tread plate, a heel seat die, devices to support said heel seat die on said carrier, and a breast gage, combined with devices to actuate the heel seat supporting devices to temporarily 80 release a heel blank, substantially as described, to enable the breast of said blank then between the tread plate and heel seat die to move against said breast gage, substantially as described. 85

6. A cross head, a second cross head, a pair of die carriers mounted on one of said cross heads, edge compressing dies sustained by said die carriers, a heel blank carrier mounted on one of said cross heads, and provided with 90 a tread plate, a heel seat die, devices to support it on said heel blank carrier, and devices to move said heel seat die vertically on or with relation to the tread plate of said carrier, and devices to change the relative 95 positions of said cross heads whereby the heel blank while being compressed edge-wise is also compressed in its thickness, substantially as described.

7. The die-carriers and the edge compressing dies located in spaces in said carriers, combined with longitudinally adjustable eyebolts removably attached to said die-carriers, and pivotally connected to said dies to hold the latter firmly in place in said carriers, substantially as described. 100

8. A heel blank carrier having a tread plate, and a connected heel seat die, combined with a spring and intermediate devices to normally keep the said heel seat die pressed toward said tread plate to pinch the heel blank frictionally, substantially as described. 110

9. A heel blank carrier having a tread plate, a heel seat die, a spring, and intermediate connections between it and said die to normally press the heel seat die onto a heel blank resting on the tread plate, a pair of die carriers, and edge compressing dies mounted thereon, combined with devices to move said heel blank carrier and heel seat die with a 115 heel blank between them into position between the said edge compressing dies, for the purposes set forth.

10. A heel blank carrier having a tread plate, a heel seat die, a spring, and intermediate connections between it and said die to normally press the heel seat die onto a heel blank resting on the tread plate, a pair of die carriers, and edge compressing dies mounted thereon, combined with devices to move said 120 heel blank carrier and heel seat die with a heel blank between them into position between the said edge compressing dies, and to then remove the compressed heel blank from 125

- between said edge compressing dies; and with a device to thereafter eject the compressed heel blank from between said tread plate and heel seat die, substantially as described.
- 5 11. In a heel compressing machine, the following instrumentalities, viz;—a breast gage, a connected heel seat die moving therewith; edge compressing dies; and mechanism for effecting change of relative positions between 10 said breast gage and heel seat die, and said edge compressing die, for the purposes set forth.
12. The heel blank carrier and its tread plate, combined with a heel seat die having a connected breast gage extended therefrom and passing below the acting face of the tread plate, substantially as described.
13. A pair of die carriers, a pair of edge compressing dies mounted thereon and having their breast corners uncovered, a heel-blank carrier having a tread plate, and a connected yielding heel seat die having an attached breast gage, combined with actuating devices to move said heel blank carrier,—it 20 clamping a heel blank,—in the direction to put a heel blank between said edge compressing dies and cause said breast gage to close the space between said edge compressing dies at their breast corners, substantially as described.
14. A pair of die carriers having strong ears 8, 8, with hardened faces, a pair of edge compressing dies mounted on said die carriers; a heel blank carrier having a tread plate, a heel blank feeder a cross head on which said heel blank carrier is mounted; and a heel seat die and attached breast gage loosely mounted on said heel blank carrier, combined with devices to actuate said cross head and said heel blank feeder, the lugs 8, 8, of the die carriers acting against the outer side of the breast gage and serving to hold the same firmly at the breast end of the edge compressing jaws, and hold the latter from springing, substantially as described.
15. A heel blank carrier, a tread plate mounted thereon, a heel seat die, devices to support said heel seat die, and connect it with said carrier, and a spring to effect the approach of the heel seat die toward the tread plate, combined with means to actuate the devices supporting the heel seat die to lift the said die away from the tread plate and thus release the heel blank, substantially as described.
16. A pair of die carriers, edge compressing dies mounted thereon, a heel blank carrier having a detachable tread plate, heel blank feeding mechanism, a table on which said feeding mechanism is mounted, combined with devices to adjust said table and feeding mechanism vertically to correspond with the thickness of the tread plate and of the heel blank to be compressed, substantially as described.
17. A heel blank carrier having a detachable tread plate, a table, and means to adjust the said table vertically, combined with a heel blank feeder, and a hopper to guide heel blanks into position to be acted upon by said feeder, substantially as described.
18. A heel blank carrier and its tread plate; and a heel blank feeder, combined with a link, a compound lever, means to adjust one part of said lever on the other part, and actuating means for said lever, the combination being and operating substantially as described to provide for feeding heels of different sizes.
19. A heel blank carrier, its tread plate; a heel seat die, its connected lever, and devices to move said lever, combined with a stationary cross head, and its attached guide behind which the heel seat die is raised, said guide also embracing and steadyng said lever, substantially as described.
20. In a machine for pressing heel blanks, heel feeding mechanism, a table on which said feeding mechanism is free to slide, said table being provided with an inclined guide arm adapted to serve as a guide for the breasts of the heel blanks in their descent, combined with a hopper case or shell adjustable on said guide arm to adapt the hopper to the thickness of the blank to be fed therefrom by said feeding mechanism, substantially as described.
21. A heel blank carrier having a tread plate to receive a heel blank to be compressed edge-wise, and a heel seat die to co-operate with the tread plate of said carrier and hold a heel blank while being put into compressed position, combined with a heel blank feeder, a connected link, a compound lever, means to adjust one part of said lever on the other part, and actuating means for said lever, the combination being and operating substantially as described to provide for feeding heels of different sizes.
22. In a heel compressing machine, a heel blank support, and a pusher frictionally connected therewith by means of a stud 25, frictional washers, and a suitable nut on said stud, substantially as described.
23. In a heel compressing machine, a pusher, devices to actuate it, a heel blank support frictionally connected thereto, and devices to temporarily connect said pusher and support in a positive manner as they are being retracted, substantially as described.
24. In a heel compressing machine, a pusher, devices to actuate it, a heel blank support frictionally connected thereto, a pawl and ratchet to temporarily connect said pusher and support in a positive manner as they are being retracted, and a device to automatically release said pawl and ratchet, substantially as described.
25. In a machine for compressing heel blanks, an edge compressing die, a carrier to supply said die with heel blanks, a pusher, and blank support, to supply said carrier with a heel blank, combined with a gage to indicate when the cam-shaft of the machine is in a defined position, and with adjustable actuating mech-

anism between a cam on said cam-shaft and the said pusher whereby the acting end of the pusher may be adjusted with relation to the blank carrier to insure the correct placing 5 of a blank upon the carrier through the movement of the pusher, substantially as described.

26. In a heel compressing machine, a heel blank carrier and a pusher to provide it with a heel blank, a main shaft and adjustable connections between it and said pusher to actuate 10 the latter, and a hand wheel by which said shaft may be turned, combined with a gage adjacent to the hand wheel to indicate the position the parts should occupy when said adjustment is effected, substantially as described.

27. A heel blank carrier, its tread plate; a heel seat die, combined with a stationary cross head, and its attached guide behind which the 20 heel seat die is raised, substantially as described.

28. In a heel compressing machine, a movable cross head, die carriers mounted thereon and attached dies, and links connected to said 25 carriers, combined with devices to adjustably connect said links with said stationary part of the machine, substantially as described.

29. A heel blank carrier having a tread plate, and also a connected heel seat die; a spring,

and devices between said heel seat die and 30 said heel blank carrier to normally keep the said heel seat die pressed toward said tread plate to thus pinch and hold the blank frictionally, and means to move said carrier, combined with devices to act on said carrier and heel seat die and force them together positively to compress the heel blank vertically or in the direction of its height, substantially as described.

30. A heel blank carrier having a tread plate, 40 a heel seat die, means to normally press the heel seat die onto a heel blank supported on the tread plate, and a pair of edge compressing dies, combined with devices to move said heel blank carrier and heel seat die, with a 45 heel blank, into position between the said edge compressing dies, and with other devices to then remove the compressed heel blank from between said edge compressing dies, substantially as described.

In testimony whereof I have signed my name to this specification in the presence of two subscribing witnesses.

JOHN J. HEYS.
